(57) **CLAIM**

The ornamental design for a shelf and key rack, as shown and described.

DESCRIPTION

FIG. 1 is a perspective view of a shelf and key rack showing our new design;

FIG. 2 is a front elevational view thereof;

FIG. 3 is a rear elevational view thereof;

FIG. 4 is a side elevational view thereof;

FIG. 5 is a top plan view thereof; and,

FIG. 6 is a bottom plan view thereof.

The broken-line disclosure in the views is understood to represent unclaimed portions of the article in which the claimed design is embodied.
